UNITED STATES PATENT OFFICE

ADOLF HEINZE, OF COSWIG ANHALT, GERMANY

ROLLER TERRACE TOWER AS PLACE OF AMUSEMENT AND RECREATION

Application filed June 2, 1927, Serial No. 196,121, and in Germany December 29, 1926.

This invention relates to towerlike buildings having stories of different size which form terraces which are adapted for use as places of amusement. This invention consists in the novel construction and combination of the parts hereinafter fully described and claimed whereby the terraces are provided with observation gangways and with rotary annular platforms which encircle the stories which project above the terraces.

In the drawings, Fig. 1 is a side view of a building constructed according to this invention. Fig. 2 is a plan view of the same. Fig. 3 is a vertical section through one side portion of a terrace and the platform supported by it, and showing the driving mechanism, and is drawn to a larger scale. Fig. 4 is a plan view of the principal parts shown in Fig. 3.

The building shown has a series of stories *a*, *b*, *c*, *d* and *e*, each upper story being smaller in area than the story below it, and forming terraces *a*¹, *b*¹, *c*¹, *d*¹ and *e*¹. The ground floor or bottom story *a* is intended as a place of amusement of any approved sort. The upper stories are also intended as places of amusement, and their interiors are provided with a suitable central passage for the elevators or stairs which afford access from one story to another. This passage also forms suitable service rooms for the various terraces, and for the motors for rotating their platforms. Annular gangways *k* are supported by the terraces around their outer portions, and are raised above the level of the terraces to which they pertain.

These gangways preferably have projecting balconies *g*, and these gangways and balconies are preferably open to the air and form places of observation of the surrounding country. Each terrace is provided with a rotary annular platform *f* which encircles the story which projects from the terrace to which the platform pertains. These platforms are graduated in size to correspond with the stories and terraces, and each platform is provided with wheels which run on circular rails *h* secured to the terrace below the platform. The central passage is provided with doors *n* or openings or windows

leading from it onto the various rotary platforms, and thence to the observation gangways and balconies. An electric motor *i* for driving each platform is arranged in the passage adjacent to the platform, and each motor drives a toothed wheel which meshes into a circular toothed rack secured to the underside of the platform.

The top of the tower is preferably provided with a fountain *o*. On the third terrace the platform may extend to the flooring *l* of the balconies, the gangway being omitted; and on the fourth terrace the balconies are omitted, so that the periphery *m* of this terrace has no projections.

What I claim is:

1. A towerlike building, comprising stories of different size which form a series of stationary terraces, circular rails secured to the terraces, rotary annular platforms provided with wheels which run on the said rails, said platforms being of different size to correspond with the terraces which support them and each platform being arranged to encircle the story which forms the next terrace above it, and annular observation gangways arranged above the level of the said terraces and supported by them and encircling the said platforms.

2. A towerlike building as set forth in claim 1, the said terraces and gangways being circular in form, and said gangways having projecting observation balconies at their peripheries.

3. A towerlike building as set forth in claim 1, and having a separate motor for driving each annular platform arranged adjacent to the platform to which it pertains.

ADOLF HEINZE.
